UNITED STATES PATENT OFFICE.

AMARIAH G. COX AND ORLANDO J. BUCK, OF CHICAGO, ILLINOIS.

DESIGN FOR CANDY OR SUGAR TONGS.

SPECIFICATION forming part of Design No. 19,504, dated December 17, 1889.

Application filed October 18, 1889. Serial No. 327,468. Term of patent 7 years.

To all whom it may concern:

Be it known that we, AMARIAH G. COX and ORLANDO J. BUCK, citizens of the United States, residing in Chicago, in the county of Cook and State of Illinois, have invented and produced a new and original Design for Candy and Sugar Tongs, of which the following is a specification, reference being had to the accompanying drawings, forming part thereof.

10 This design relates to that variety of tongs which are commonly used with candy or lump sugar, and which are generally formed of sheet metal.

15 It consists in fashioning each half of such tongs in the semblance of a human hand and forearm.

The accompanying drawings show at Figure 1 a pair of tongs embodying our design in the extended or unbent condition. Fig. 2 20 shows the tongs as folded or doubled ready for use.

In said drawings, *a* represents the gripping parts or points of the tongs. These are fashioned to represent the human hand, and the adjacent portions *b* are shaped to represent 25 the human forearm. The latter portions are united at the center by the part *c*. At its edges said part *c* may be fastened to represent the scalloped or lace trimming of a sleeve, as shown at *d*. 30

We claim—

In a design for candy and sugar tongs, the part *a*, shaped to represent the human hand, the part *b*, shaped to represent the human forearm, and the part *c*, having an ornamental 35 border *d*, as shown.

AMARIAH G. COX.
ORLANDO J. BUCK.
